(57) **CLAIM**

The ornamental design of a hose adapter, as shown and described.

DESCRIPTION

FIG. 1 is a front left top perspective view of a hose adapter, showing the new design in a closed state;

FIG. 2 is a front right top perspective view of the hose adapter of FIG. 1;

FIG. 3 is a rear left top perspective view of the hose adapter of FIG. 1;

FIG. 4 is a rear right top perspective view of the hose adapter of FIG. 1;

FIG. 5 is a rear left bottom perspective view of the hose adapter of FIG. 1;

FIG. 6 is a rear right bottom perspective view of the hose adapter of FIG. 1;

FIG. 7 is a front left bottom perspective view of the hose adapter of FIG. 1;

FIG. 8 is a front right bottom perspective view of the hose adapter of FIG. 1;

FIG. 9 is a front view of the hose adapter of FIG. 1;

FIG. 10 is a back view of the hose adapter of FIG. 1;

FIG. 11 is a left side view of the hose adapter of FIG. 1;

FIG. 12 is a right side view of the hose adapter of FIG. 1;

FIG. 13 is a top view of the hose adapter of FIG. 1;

FIG. 14 is a bottom view of the hose adapter of FIG. 1;

FIG. 15 is a rear left top perspective view of a hose adapter, showing the new design in an open state;

FIG. 16 is a rear right top perspective view of the hose adapter of FIG. 15;

FIG. 17 is a front left top perspective view of the hose adapter of FIG. 15;

FIG. 18 is a front right top perspective view of the hose adapter of FIG. 15;

FIG. 19 is a front left bottom perspective view of the hose adapter of FIG. 15;

FIG. 20 is a front right bottom perspective view of the hose adapter of FIG. 15;

FIG. 21 is a rear left bottom perspective view of the hose adapter of FIG. 15;

FIG. 22 is a rear right bottom perspective view of the hose adapter of FIG. 15;

FIG. 23 is a front view of the hose adapter of FIG. 15;

FIG. 24 is a back view of the hose adapter of FIG. 15;

FIG. 25 is a left side view of the hose adapter of FIG. 15;

FIG. 26 is a right side view of the hose adapter of FIG. 15;

FIG. 27 is a top view of the hose adapter of FIG. 15; and,

FIG. 28 is a bottom view of the hose adapter of FIG. 15.

(Continued)

Any broken lines in the figures show portions of the hose adapter that form no part of the claimed design.
